UNITED STATES PATENT OFFICE

HENRY THOMAS, OF LONDON, ENGLAND, ASSIGNOR TO U. S. SLICING MACHINE COMPANY, OF LA PORTE, INDIANA, A CORPORATION OF INDIANA

DISPLAY TRAY FOR SLICING MACHINES

Application filed December 15, 1925, Serial No. 75,630, and in Great Britain December 30, 1924.

This invention relates to display trays, particularly for cooked meats, used on machines for slicing meat or other foodstuffs.

Such a display tray is generally secured on the meat table of a slicing machine by means of bayonet joints, but this method of securing the tray on the meat table has the disadvantage that the locking arrangement is not entirely positive, owing to the wear which takes place between the interlocking members, due to the vibration caused by the operation of the machine.

One object of the present invention is to obviate this disadvantage by providing means for positively locking the display tray to the meat table and another object of the invention is to provide improved means for clamping the substance to be sliced in position on the tray.

To the attainment of the aforesaid objects, according to the present invention, I provide a display tray of a slicing machine which can be locked to the substance-carrying table by co-acting movable means and stationary means in such manner that the tray, when locked in position, cannot be removed from off the machine until and unless said movable means is operated.

Said movable means may consist of a turnable member, or members, adapted to co-act with a fixed member, or members. Thus, for example, a cam member, or members, pivoted to the display tray may be adapted to co-act with one, or more fixed abutments on said table.

The cramp for fastening the substance on to the display tray is adjustable towards and away from the tray, means being provided for locking the cramp in its adjusted positions. The cramp may be mounted on a supporting member adapted to be moved upwards and downwards relatively to the display tray, in which case means are provided for locking said supporting member in its adjusted positions. Preferably, the cramp is supported by an arm secured to a column, which is slidable in a bracket fixed to the display tray, a cam member, pivoted on said bracket, being adapted to co-act with the column to secure it in its adjusted positions.

Means may be provided whereby increased pressure can be applied to the substance by the cramp after the latter has been initially adjusted into contact with the substance, said means, in one form, consisting of a lever pivoted to the cramp supporting arm and formed with an arcuate slot in which a pin secured to an arm of the cramp is engaged. Means may also be provided for use when substances of different shapes and different widths are to be arranged on the display tray, said means preferably consisting of side members or plates removably arranged on the tray and, if desired, combined with means for their easy and quick removal from the tray as described hereafter.

Two constructional embodiments of my invention applied to meat slicing machines are illustrated, by way of example, on the annexed drawings, whereon:

Fig. 1 is a front elevation of a display tray fixed in position on the usual meat table of a slicing machine;

Fig. 2 is a plan view corresponding to Fig. 1;

Fig. 3 is a fragmentary end elevation, partly in section, corresponding to Fig. 1;

Fig. 4 is a fragmentary view showing how removable side plate is used in combination with the display tray when meats of round section are to be arranged thereon;

Fig. 5 is a fragmentary view of modified adjusting means for the meat cramp; and

Fig. 6 is an end elevation corresponding to Fig. 5.

Referring to Figs. 1 to 3:

The display tray comprises a base portion 1 having an upturned side 2 provided, at one side, with a turned-over part 3 which is adapted to serve as a handle when removing or replacing the display tray. A bracket 4 is secured to the side 2 and comprises two hooked parts 5 and 6, a boss 7, and a boss 8 at one of its extremities. The boss 8 is formed with a projecting lug 9 which is split at 10, a cam 11, provided with a handle 12, being arranged between the two parts of the lug 9 and rotatably mounted on a pin 13 passing through an aperture in one of said parts and screwed into the other part. A lever 14, 100

formed at one end with a cam 15, is pivoted to the bracket 4 by means of a pin 16 screwed into the boss 7, said cam being adapted to coact with an upright 17 fixed into the meat table 18, so as to secure the display tray firmly on said table. The upright 17 is engaged by the hook 6 on the bracket 4 and another upright 19, also fixed into the meat table, is engaged by the hook 5 on said bracket. The 10 cam 15 co-acts with the upright 17 in such a manner that if the display tray is arranged carelessly in position with its hooks 5 and 6 engaging said uprights, the operation of the lever 14 will have the effect of pulling the display tray into its proper position and positively locking it therein.

The boss 8 is bored at 20 so as to accommodate a vertical column or support 21, which is slidable therein and is attached at its upper end to a substantially horizontal arm 22 adapted to carry a meat cramp as described hereafter. The column 21 is formed with a longitudinal groove 23 in which the cam 11 is engaged for the purpose of preventing rotation of said column and for fixing the latter in its adjusted positions when the handle 12 is turned in such a direction that the cam bears hard against the bottom of the groove 23. The arm 22 is formed with a downwardly depending apertured lug 25 wherein an arm 26 on a T-shaped meat cramp 27, formed with corrugations 28, is slidably arranged, said arm being adapted to be secured in its adjusted positions by means of a pin 29 screwed into the arm and having a head 30 formed with a shoulder adapted to bear against the face 25^a of said lug.

The display tray, as shown in plan in Fig. 2, is adapted to be used for meat having a flat surface and in order to adapt the tray for use in supporting circular pieces of meat, for example, we provide a removable side plate 31 shown in position in Fig. 4, said plate being removably secured to the side 2 of the display tray by means of screws 32 passing through key-hole slots, whereby the position of the plate 31 can be adjusted. It will be understood that said plate can be made of various shapes for use with meats of different sections.

In order to provide for meats of different widths, the base 1 of the display tray is formed with a number of key-hole slots 33, 34 and 35, which are adapted to be engaged by the T-head 36 of a bolt 37 slideable in an aperture 38 formed in a side plate 39 similar to the plate 31. The upper end of the bolt 37 screws into a nut member 40 which, in turn is screwed into a threaded aperture 41 in the side plate 39, a handle 42 being secured to the member 40. The nut member is screwed to the opposite hand from the bolt 37 so that the effect of turning the handle 42 in a direction to cause the nut member to move downwards is to cause the T-headed bolt 37 also to move downwards and vice versa. The

side plate 39 is applied to the display tray with the T-head engaging in one or other of the key-hole slots 33, 34, or 35, when by turning the handle 42 in the required direction the base 1 of the display tray is firmly and quickly gripped between the top of the T-head 36 and the under side of the side-plate. As in the case of the side-plate 31, the side-plate 39 can be variously shaped to suit different shaped pieces of meat.

A modified device for fixing the meat cramp 27 in adjusted positions and for applying additional pressure to the meat after the cramp has been initially adjusted into contact with the meat is illustrated in Figs. 5 and 6, wherein the arm 22 will be seen to be slotted at 43 at its front end while a lever 44, provided with a handle 45, is pivotally mounted on a pin 45^a in the slot. The upper end of the arm 26 is also slotted and the lever 44 engages in said slot and is secured therein by means of a pin 46 fixed in the bifurcated part of the arm 26 and engaging in an arcuate aperture 47 in said lever. The meat cramp is shown in its lowest position in Fig. 5 and it will be obvious that by turning the handle 45 to the left the bar 26 and meat cramp will be raised, while by turning said handle in the opposite direction the meat cramp will be lowered. The engagement of the pin 46 in the aperture 47 allows increased pressure to be applied to the meat by turning the handle still further to the right after the meat cramp has once come into contact with the top of the meat.

Having now fully described my invention what I claim and desire to secure by Letters Patent is:—

1. In a slicing machine, a substance-carrying table, a display tray arranged thereon, two fixed abutments on said table, hook members on said tray for engaging with said abutments, and a cam member, turnably mounted on said tray, for co-acting with one of said abutments to positively lock the tray against removal from off the machine until and unless said cam member is operated.

2. In a slicing machine, a substance-carrying table, a display tray arranged thereon, a movable means on said tray for positively locking the latter against removal from off the slicing machine until and unless said means is operated, a cramp on the tray for securing the substance thereon, means for adjusting said cramp towards and away from the tray, means for locking the cramp in its adjusted positions, and means for applying increased pressure to the substance by the cramp after the latter has been initially adjusted into contact with the substance.

3. In a slicing machine, a substance-carrying table, a display tray arranged thereon, a movable means on said tray for positively locking the latter against removal from off the slicing machine until and unless said

means is operated, a hollow boss on the tray, an arm extending over the tray, a column, for supporting said arm, movable upwards or downwards in said boss relatively to the tray, a turnable member for locking the column in its adjusted positions, an aperture in said arm, a cramp for securing the substance on the tray, an arm on said cramp slideable upwards or downwards in said aperture, and means for locking the arm on the cramp in its adjusted positions.

4. In a slicing machine, a substance-carrying table, a display tray arranged thereon, fixed means on said table, movable means on said display tray adapted to co-act with the fixed means to positively lock the tray against removal from off the machine until and unless said movable means is operated, an arm extending across the tray, a cramp, for securing the substance on the tray, mounted on said arm, a hollow boss on the tray, a column, for supporting said arm, movable upwards or downwards in said boss relatively to the tray, and a turnable member for locking the column in its adjusted positions against movement in either direction.

5. In a slicing machine, a substance-carrying table, a display tray arranged thereon, fixed means on said table, movable means on said display tray adapted to co-act with the fixed means to positively lock the tray against removal from off the machine until and unless said movable means is operated, a cramp on the tray for securing the substance thereon, means for adjusting said cramp towards and away from the tray, means for locking the cramp in its adjusted positions, and means for applying increased pressure to the substance by the cramp after the latter has been initially adjusted into contact with the substance.

6. In a slicing machine, a substance-carrying table, a display tray arranged thereon, fixed means on said table, movable means on said display tray adapted to co-act with the fixed means to positively lock the tray against removal from off the machine until and unless said movable means is operated, a hollow boss on the tray, an arm extending over the tray, a column, for supporting said arm, movable upwards or downwards in said boss relatively to the tray, a turnable member for locking the column in its adjusted positions, an aperture in said arm, a cramp for securing the substance to the tray, an arm on said cramp slideable upwards or downwards in said aperture, and means for locking the arm on the cramp in its adjusted position.

65. 7. In a slicing machine, a substance-carrying table, a display tray arranged thereon, fixed abutments on said table, a member on said tray adapted to engage one of said abutments, a turnable member on said tray adapted to engage the other abutment to positively

lock the tray against removal from off the machine until and unless said turnable member is operated, a cramp on the tray for securing the substance thereon, means for adjusting said cramp towards and away from the tray, and means for locking the cramp in its adjusted positions against movement either towards or away from said tray.

8. In a slicing machine, a substance-carrying table, a display tray arranged thereon, fixed abutments on said table, a member on said tray adapted to engage one of said abutments, a turnable member on said tray adapted to engage the other abutment to positively lock the tray against removal from off the machine until and unless said turnable member is operated, an arm extending across the tray, a cramp, for securing the substance on the tray, mounted on said arm, a hollow boss on the tray, a column, for supporting said arm, movable upwards or downwards in said boss relatively to the tray, and a turnable member for locking the column in its adjusted positions.

9. In a slicing machine, a substance-carrying table, a display tray arranged thereon, fixed abutments on said table, a member on said tray adapted to engage one of said abutments, a turnable member on said tray adapted to engage the other abutment to positively lock the tray against removal from off the machine until and unless said turnable member is operated, a cramp on the tray for securing the substance thereon, means for adjusting said cramp towards and away from the tray, means for locking the cramp in its adjusted positions, and means for applying increased pressure to the substance by the cramp after the latter has been initially adjusted into contact with the substance.

10. In a slicing machine, a substance-carrying table, a display tray arranged thereon, fixed abutments on said table, a member on said tray adapted to engage one of said abutments, a turnable member on said tray adapted to engage the other abutment to positively lock the tray against removal from off the machine until and unless said turnable member is operated, supporting means movable upwards or downwards relatively to the tray, means for locking the supporting means in adjusted positions, a cramp, for securing the substance on said tray, carried by and adjustable upwards or downwards relatively to said supporting means, and means for locking said cramp in its adjusted positions.

11. In a slicing machine, a substance-carrying table, a display tray arranged thereon, fixed abutments on said table, a member on said tray adapted to engage one of said abutments, a turnable member on said tray adapted to engage the other abutment to positively lock the tray against removal from off the machine until and unless said turnable member is operated, a hollow boss on the tray, an

arm extending over the tray, a column, for supporting said arm, movable upwards or downwards in said boss relatively to the tray, a turnable member for locking the column in its adjusted positions, an aperture in said arm, a cramp for securing the substance on the tray, an arm on said cramp slideable upwards or downwards in said aperture, and means for locking the arm on the cramp in its adjusted positions.

12. In a slicing machine, a substance-carrying table, a display tray arranged thereon, two fixed abutments on said table, hook members on said tray for engaging with said abutments, a cam member, turnably mounted on said tray, for co-acting with one of said abutments to positively lock the tray against removal from off the machine until and unless said cam member is operated, a cramp on the tray for securing the substance thereon, means for adjusting said cramp towards and away from the tray, and means for locking the cramp in its adjusted positions against movement in a direction either towards or away from said tray.

13. In a slicing machine, a substance-carrying table, a display tray arranged thereon, two fixed abutments on said table, hook members on said tray for engaging with said abutments, a cam member, turnably mounted on said tray, for co-acting with one of said abutments to positively lock the tray against removal from off the machine until and unless said cam member is operated, an arm extending across the tray, a cramp, for securing the substance on the tray, mounted on said arm, a hollow boss on the tray, a column, for supporting said arm, movable upwards or downwards in said boss relatively to the tray, and a turnable member for locking the column in its adjusted positions.

14. In a slicing machine, a substance-carrying table, a display tray arranged thereon, two fixed abutments on said table, hook members on said tray for engaging with said abutments, a cam member, turnably mounted on said tray, for co-acting with one of said abutments to positively lock the tray against removal from off the machine until and unless said cam member is operated, a cramp on the tray for securing the substance thereon, means for adjusting said cramp towards and away from the tray, means for locking the cramp in its adjusted positions, and means for applying increased pressure to the substance by the cramp after the latter has been initially adjusted into contact with the substance.

15. In a slicing machine, a substance-carrying table, a display tray arranged thereon, two fixed abutments on said table, hook members on said tray, for engaging with said abutments, a cam member, turnably mounted on said tray, for co-acting with one of said abutments to positively lock the tray against

removal from off the machine until and unless said cam member is operated, supporting means movable upwards or downwards relatively to the tray, means for locking the supporting means in adjusted positions, a cramp, for securing the substance on said tray, carried by and adjustable upwards or downwards relatively to said supporting means, and means for locking said cramp in its adjusted positions.

16. In a slicing machine, a substance-carrying table, a display tray arranged thereon, two fixed abutments on said table, hook members on said tray for engaging with said abutments, a cam member, turnably mounted on said tray, for co-acting with one of said abutments to positively lock the tray against removal from off the machine until and unless said cam member is operated, a hollow boss on the tray, an arm extending over the tray, a column, for supporting said arm, movable upwards or downwards in said boss relatively to the tray, a turnable member for locking the column in its adjusted positions, an aperture in said arm, a cramp for securing the substance on the tray, an arm on said cramp slideable upwards or downwards in said aperture, and means for locking the arm on the cramp in its adjusted positions.

17. In a slicing machine, a substance-carrying table, a display tray arranged thereon, a movable means on said tray for positively locking the latter against removal from off the slicing machine until and unless said means is operated, a cramp on the tray for securing the substance thereon, means for adjusting said cramp towards and away from the tray, means for locking the cramp in its adjusted positions, means whereby substances of different widths and shapes can be arranged on the display tray, and means for securing said last mentioned means to the tray.

18. In a slicing machine, a substance-carrying table, a display tray arranged thereon, a movable means on said tray for positively locking the latter against removal from off the slicing machine until and unless said means is operated, an arm extending across the tray, a cramp, for securing the substance on the tray, mounted on said arm, a hollow boss on the tray, a column, for supporting said arm, movable upwards or downwards in said boss relatively to the tray, a turnable member for locking the column in its adjusted positions, means whereby substances of different widths and shapes can be arranged on the display tray, and means for securing said last mentioned means to the tray.

19. In a slicing machine, a substance-carrying table, a display tray arranged thereon, a movable means on said tray for positively locking the latter against removal from off the slicing machine until and unless said means is operated, a cramp on the tray for

securing the substance thereon, means for adjusting said cramp towards and away from the tray, means for locking the cramp in its adjusted positions, means for applying increased pressure to the substance by the cramp after the latter has been initially adjusted into contact with the substance, means whereby substances of different widths and shapes can be arranged on the display tray, and means for securing said last mentioned means to the tray.

20. In a slicing machine, a table, a display tray and means for securing the tray upon the table, comprising vertically projecting posts on the table, means on the display tray embracing the posts, and means associated with the post embracing means for locking the same in embracing relation with the posts.

21. In a slicing machine, a table, a display tray and means for securing the tray upon the table, comprising vertically projecting posts on the table, means on the display tray embracing the posts, and means associated with the post embracing means for locking the same in embracing relation with the posts, comprising a cam pivoted to the post embracing means with is camming surface in wiping contact with the side of one of the posts.

22. In a slicing machine, a display tray, a mounting therefor and means for locking the tray to the mounting, comprising a vertical projecting wall on the tray, spaced hooks mounted to said wall, spaced posts on the mounting projecting vertically thereof parallel with the wall on the tray and in position to be engaged by said hooks, and a cam lever pivoted to the wall of the tray with its camming surface in wiping contact with the side of one of the posts.

23. In a slicing machine, a substance-carrying table, a display tray arranged thereon, means on said tray for locking said tray on said slicing machine, a hollow boss on said tray, an arm extending over the tray, a column for supporting said arm movable upwards or downwards in said boss relatively to the tray, a turnable member for locking the column in its adjusted positions, an aperture in said arm, a cramp for securing the substance on the tray, an arm on said cramp slideable upwards or downwards in said aperture, means for locking the arm on the cramp in its adjusted positions, means whereby substances of different widths and shapes can be arranged on the display tray, and means for securing said last-mentioned means to the tray.

24. A slicing machine comprising a support, a tray removably mounted on said support by means located on one side of said support, said means forming the sole connection between said support and the tray, a cramp adjustably mounted on said tray adapted to hold thereon the substance to be sliced, said cramp comprising a pivoted mem-

ber, and means for actuating the pivoted member to move the cramp towards the tray independently of said adjustable mounting for said cramp.

25. In a slicing machine, a substance-carrying table, a display tray arranged thereon, a movable means on said tray for positively locking the latter against removal from off the slicing machine until and unless said means is operated, an arm extending across the tray, a cramp, for securing the substance on the tray, mounted on said arm, a hollow boss on the tray, a column, for supporting said arm, movable upwards or downwards in said boss relatively to the tray, and a turnable member for locking the column in its adjusted positions.

In testimony whereof I affix my signature.
HENRY THOMAS.
